UNITED STATES PATENT OFFICE.

GENTRY L. ROWSEY, OF QUINCY, ILLINOIS, ASSIGNOR TO THE ILLINOIS REFINING MACHINERY COMPANY, OF QUINCY, ILLINOIS, A FIRM COMPOSED OF GENTRY L. ROWSEY, LEO F. LECHTERBERG, LAWRENCE A. LECHTERBERG, AND WILLIAM T. LECHTERBERG.

APPARATUS FOR TREATING HYDROCARBON-OILS.

1,235,384.

Specification of Letters Patent.

Patented July 31, 1917.

Application filed July 1, 1916. Serial No. 107,093.

To all whom it may concern:

Be it known that I, GENTRY L. Rowsey, a citizen of the United States of America, a resident of Quincy, in the county of Adams, 5 State of Illinois, have invented certain new and useful Improvements in Apparatus for Treating Hydrocarbon-Oils, of which the following is a full, clear, and exact description, reference being had to the accompanying drawings, forming a part of this specification.

My invention relates to an apparatus for use in converting hydrocarbon oils of high boiling points into hydrocarbons of lower 15 boiling points of the same series, the invention having for its object to provide a mild cracking operation and produce a distillate preferably of from 48° to 50° gravity Baumé.

20 Figure I is a view in elevation, partly in vertical section, of my apparatus, the furnace housing the still portion of the apparatus being omitted.

Fig. II is a longitudinal vertical section 25 taken on line II—II, Fig. IV, showing the still in side elevation and the furnace in section.

Fig. III is a longitudinal vertical section 30 taken on line III—III, Fig. IV centrally of the still and its furnace.

Fig. IV is a cross section through the still and its furnace.

In the drawings, A designates the still of 35 my apparatus as a whole, this still comprising bottom manifolds 1, a top manifold 2 and series of connecting pipes 3 providing communication between said bottom manifolds and said top manifold. There are preferably two of the bottom manifolds 1, 40 extending longitudinally of the apparatus and spaced apart from each other, as seen most clearly in Fig. IV. The connecting pipes 3 are inclined upwardly from said lower manifolds to the upper manifold.

45 4 designates an oil supply pipe for delivering oil into one of the lower manifolds 1, and 6 is a steam conducting pipe through which steam is admitted to said manifold, the flow through these pipes being controlled by valves 5 and 7. The said pipes 4 and 6 and their valves are duplicated for 50 supplying oil and steam to the second lower manifold 1.

8 designates a distillate conducting pipe leading from the upper manifold 2, first 55 in a downward course at the forward end of the still and then in an upwardly and rearwardly inclined course to the rear of the still, the inclined portion of said pipe preferably passing between the series of 60 pipes 3 providing communication from the lower manifolds to the upper manifolds of the still.

9 designates a primary condenser coil with which the upper end of the distillate conducting pipe 8 communicates. This coil is connected to the distillate conducting pipe at its lower end and its discharge end is located uppermost. The coil 9 is arranged within a condenser pan 10 having water 70 inlet and overflow connections 11 and 12 which provide for a continuous circulation of water through the pan 10 to constantly exert a cooling influence of the primary condenser coil.

75 13 designates a secondary condenser coil, the upper end of which has communication with the upper end of the primary condenser coil by a connecting pipe 14, the said secondary condenser coil being arranged in a 80 condenser pan 15 having water inlet and overflow connections 16 and 17. At the discharge end of the secondary condenser coil is a valve 18.

19 designates a separator into which the 85 condensed distillate is delivered from the secondary condenser, this separator being provided with a suitable gage 20 to constantly indicate the quantity of condensed distillate in the separator, and the separator 90 has connected to it an outlet pipe 21, having a valve 22, through which the contents of the separator may be drawn during the operation of the apparatus.

23 designates a gas conducting pipe leading 95 from the separator 20. This gas conducting pipe is provided with a valve 24 and leads to a compressor 25. The said compressor serves to draw the permanent or incondensable gases from the separator 20 100 through the pipe 23 and deliver them through a pipe 26 to a dome 27 surmounting the upper manifold 2 of the still A. The said pipe 26 is provided with a suitable valve 28.

105 B designates a furnace within which the

still is housed. At the bottom of this furnace is a combustion chamber 29 in which fuel of any preferable description may be burned to heat the still and its contents. 5 Hot air ducts 30 lead from said combustion chamber to flues 31 which in turn lead to flues 32 surrounding the upwardly extending pipes 3 of the still. The flues 32 have communication at their upper ends with longitudinal draft flues 33.

10 In order that there may be uniform heating of the pipes 3, I provide a damper 34 (see Figs. III and IV) for each duct 30 leading from the combustion chamber 29, the dampers being intended to be operated individually by any suitable means, for example, a shift rod 35 connected to each damper and leading to the exterior of the furnace where it is attached to an operating lever 36.

15 The upwardly inclined distillate conducting pipe 8 of the still is located in a flue 37 inclined correspondingly to the inclination of said pipe, and heat is supplied in said flue by suitable means, such as a fuel conducting pipe 38, having a burner nozzle 39, see Fig. III. Oil, gas or other suitable fuel may be delivered to said burner for consumption to provide for the maintenance of a high degree of temperature in the flue 37 25 around the distillate conducting pipe 8.

30 In the practical use of my oil treating apparatus, the hydrocarbon oil to be treated is charged into the lower manifolds 1, through the pipes 4, and rises through the upwardly extending pipes 3 into the top manifold 2. The oil is so charged into the still that the upper manifold will only be partially filled, say about one-third, and as the oil is distilled additional oil is forced into the still 35 to maintain about the same level in the upper manifold as mentioned.

35 Distillation of the oil is occasioned by creating the proper heat in the combustion chamber 29 and the flues in communication therewith and surrounding the upwardly 40 extending still pipes 3.

45 At the commencement of distillation, steam is admitted into the bottom manifolds 1 through the pipes 6 and travels with the oil in its upward course in the still, the steam serving the purpose of retarding decomposition and giving better odor and color to the distillate.

50 The vapors of distillation pass from the top manifold 2 of the still into the distillate conducting pipe 8, following the course of this pipe first in a downwardly direction and then in an upwardly inclined direction to the primary condenser coil 9. In said primary condenser coil the unconverted and 55 partially converted vapors that will condense into hydrocarbons of high boiling points are condensed and returned by reverse flow from the primary condenser into the distillate 60 conducting pipe 8, which pipe is maintained

at or above oil cracking temperature, and, as a consequence, the condensed vapors delivered back thereto are revaporized and cracked to be returned to the primary condenser in the form of hydrocarbons of lower 70 boiling points, which will pass to the secondary condenser and thereafter be collected in the separator 19.

75 The permanent gases, or incondensable vapors, pass through both of the condensers 9 and 13 and into the separator 19, and these gases are drawn by the compressor 25 through the pipe 23 and forced through the pipe 26 into the dome 27 of the upper manifold 2 of the still. The permanent gases are 80 thereby kept in the apparatus and due to their retention the formation of such gases is retarded, this effect being obtained on the supposition that if sufficient permanent gases are present in the apparatus an equilibrium will occur after which no further permanent gases will be produced.

85 During the operation of my apparatus I maintain a pressure of from 30 to 200 pounds in the apparatus, this pressure varying according to the nature of the oil being treated and the amount of steam introduced into the apparatus. The temperature maintained in the manifold 2 of the still may vary from 70° to 1200° Fahrenheit.

90 By the admission of steam into the still I retard decomposition of the oil, and this is desirable for the reason that it is the intention to crack the oil mildly, converting it 95 into a distillate of from 48° to 50° Baumé 100 gravity, and of low boiling point. The oil treated may be of any nature of from light fuel oil to heavy residuum and the extent of the cracking is regulated by the pressure and temperature maintained and the amount of 105 steam introduced into the apparatus. It is to be understood that by the use of my apparatus, I do not desire to convert oil 110 into a distillate of the olefin series and also that by reason of the use of steam I do not produce a product of dry distillation but a distillate which contains a high percentage 115 of hydrocarbons of the paraffin series.

120 In order to prevent the passage of unconverted oil from the top manifold of the still into the distillate conducting pipe I provide in said pipe adjacent to the outlet of said manifold a body 40 of retarding material, such for example, as animal charcoal or bone phosphate. I also provide a body 41 of similar material in said pipe at the junction of its downwardly extending and upwardly inclined portions. Any small quantity of oil that may reach this point and pass gradually into the upwardly inclined portion of 125 the distillate conducting pipe 8 will be cracked, inasmuch as such pipe is maintained at or above the cracking temperature.

I claim:

1. An apparatus of the character de- 130

- scribed comprising a still, primary and secondary condensers arranged in series, a distillate conducting conduit leading from the top of the still to said primary condenser, said conduit being in part located below the point of its connection with said still to prevent the flow of condensate from the conduit to the still and being so connected to said primary condenser as to provide for simultaneous delivery of vapors of distillation from the still to the primary condenser and reflux flow of condensate of heavy vapors of distillation from the primary condenser to said conduit, and means for heating said conduit to vaporize and crack the condensate of heavy vapors delivered thereto from the primary condenser.
- 5 2. An apparatus of the character described comprising a still, primary and secondary condensers arranged in series, a distillate conducting conduit leading from said still to said primary condenser, said conduit being so disposed as to prevent flow of condensate therethrough to said still and being so connected to said primary condenser as to provide for delivery of vapors of distillation from the still to the primary condenser and reflux flow of condensate of heavy vapors of distillation from the primary condenser to said conduit, and means for heating said conduit to vaporize and crack the condensate delivered thereto from the primary condenser.
- 10 3. An apparatus of the character described comprising a still, primary and secondary condensers arranged in series, a distillate conducting conduit leading from said still to said primary condenser, said conduit being in part located beneath the point of its connection to said still to prevent flow of condensate through the conduit to the still and connected to the bottom of said condenser to permit reflux flow of condensate of heavy vapors of distillation from the primary condenser to the conduit, and means for heating said conduit to vaporize and crack the condensate of heavy vapors.
- 15 4. In an apparatus of the character described comprising a still, primary and secondary condensers arranged in series, a distillate conducting conduit leading from said still to said primary condenser, said conduit being in part located beneath the point of its connection to said still to prevent flow of condensate through the conduit to the still and connected to the bottom of said condenser to permit reflux flow of condensate of heavy vapors of distillation from the primary condenser to the conduit, and means for heating said conduit to vaporize and crack the condensate of heavy vapors.
